US00D323250S

United States Patent [19]

Leib

[11] Patent Number: Des. 323,250

[45] Date of Patent: ** Jan. 21, 1992

[54] ARM CHAIR

[76] Inventor: Roger K. Leib, 208 S. McCadden Pl.,
Los Angeles, Calif. 90004

[**] Term: 14 Years

[21] Appl. No.: 186,125

[22] Filed: Apr. 25, 1988

[52] U.S. Cl. D6/373

[58] Field of Search D6/373, 367, 380, 378;
294/445
